UNITED STATES PATENT OFFICE.

SAMUEL C. BAUGHN, OF CANALOU, MISSOURI, ASSIGNOR OF ONE-HALF TO J. W. BAUGHN AND G. A. WRIGHT AND ONE-FOURTH TO SANTFORD M. GREER, ALL OF CANALOU, MISSOURI.

CATTLE-GUARD.

947,691.

Specification of Letters Patent. Patented Jan. 25, 1910.

Application filed May 19, 1909. Serial No. 496,982.

To all whom it may concern:

Be it known that I, SAMUEL C. BAUGHN, a citizen of the United States, residing at Canalou, in the county of New Madrid and State of Missouri, have invented a new and useful Cattle-Guard, of which the following is a specification.

This invention relates to cattle-guards for railroads, the object of the invention being 10 to provide a guard of this type utilizing a series of pickets designed to be actuated by an animal approaching the guard, so as to be elevated in front of the animal and prevent it from leaving an inclosure through which 15 the track extends.

Another object is to provide a guard of this type utilizing pickets so shaped as to lie flat upon the ties where they cannot be engaged by any parts which may be 20 dragged by a car or cars passing over the guard.

A still further object is to provide novel means for guiding the guard during the movement thereof.

25 A still further object is to provide platforms of novel form for receiving the weight of the animal approaching the guard, said platforms being capable of a yielding action with relation to the balance 30 of the mechanism of the guard.

With these and other objects in view the invention consists of certain novel details of construction and combinations of parts hereinafter more fully described and pointed out in the claims.

35 In the accompanying drawings the preferred form of the invention has been shown.

In said drawings:—Figure 1 is a plan 40 view of a cattle-guard embodying the present improvements, the pickets being shown in their normal or lowered position. Fig. 2 is a section on line A—B Fig. 1, the pickets being shown extended upwardly. Fig. 45 3 is a perspective view of one of the platform sections, said section being inverted.

Referring to the figures by characters of reference A designates the ties and B the rails of a track, there being straps 1 secured upon one of the ties and terminating in loops 2 and 3 constituting bearings, these loops being depressed so as to lie below the plane occupied by the upper faces of the ties A. The loops 3 constitute bearings for 55 a rock bar 4 extending under the rails B

and parallel with the ties, said bar having a series of pickets 5 extending therefrom, said pickets being so shaped as to bear flat upon the upper faces of the ties A disposed in the path thereof. An arm 6 extends 60 from the rock-bar 4 and has a weight 7 thereon designed to hold the pickets normally in lowered position. The loops 2 constitute bearings for a second rock-bar 8, which also extends under the rails B, there 65 being an angular arm 9 connected at one end to this rock-bar and extended under one of the ties and thence upwardly, the upper free end of the arm being secured to one end of a chain 10 or the like which is 70 wrapped one or more times about the rock-bar 4, said chain being secured to the bar.

Openings are formed within the bar 8 at points between the rails B and also those portions of the bar extending beyond the 75 rails. These openings are designed to receive spring arms 12, preferably arranged in pairs and each arm having a crooked portion 13 which is secured in any suitable manner to the bottom face of a platform section 14. 80 One of these sections extends between the rails and the other sections are disposed at the outer sides thereof. The arms and their crooked portions constitute yielding supports for the platform sections, and, as a result, when the weight of an animal is applied to one of the sections, the guard mechanism 85 will not be operated until after the platform section has yielded to a slight extent. This yielding action will sometimes be sufficient to 90 cause the animal to turn away from the guard, but, should it not be sufficient, the application of additional weight thereto will result in the actuation of the guard. When the rock-bar 8 is partly rotated by the depression of one or more of the platform sections, the arm 9 moves upwardly at its free 95 end and thus pulls upon the flexible element 10 which is therefore caused to unwind from the rock-bar 4. Said bar will thus be caused 100 to partly rotate and the pickets 5 will be swung upwardly as indicated by full lines in Fig. 2. The arm 6 and weight 7 will also be elevated. When the weight is removed from the platform sections the parts 6 and 7 will 105 operate to automatically return the mechanism to its initial position.

In order to prevent lateral displacement of the rock-bar 4 and the pickets, a guide strip 15 is secured to the tie A on which the 110

straps 1 are fastened, and this strip curves downwardly partly around the rock-bar 4, there being a slot 16 therein within which one of the pickets works. This picket is 5 always located within the slot and it will therefore be apparent that the strip 15 not only serves to prevent the bar 4 from shifting in the direction of its length, but it also serves to limit the upward swinging movement of the pickets.

It is of course to be understood that various changes may be made in the construction and arrangement of the parts without departing from the spirit or sacrificing the 15 advantages of the invention.

What is claimed is:—

1. A cattle-guard including guard members mounted for swinging movement, a de- 20 pressible actuating device, and elastic means for transmitting motion from said device to the guard members.

2. A cattle-guard including spaced rock- 25 ing members, a flexible element wrapped about one of said members and secured thereto, an arm extending from the other member and secured to the flexible element, a

platform, elastic means for transmitting motion therefrom to the rocking member from which the arm extends, and guard members projecting from and movable with the other 30 rocking member.

3. A cattle-guard including a rock-bar, spring arms detachably connected thereto, platform sections secured upon the arms, an arm extending from said rock-bar, a second 35 rock-bar, guard members extending therefrom and movable therewith, and a flexible element wrapped about and secured to said last mentioned rock-bar and secured to and disposed to be actuated by the arm.

4. A cattle-guard including a rock-bar, a series of swinging guard members actuated thereby, and a depressible platform and elastic means for transmitting motion from the 40 platform to the rock bar.

In testimony that I claim the foregoing as my own, I have hereto affixed my signature in the presence of two witnesses.

SAMUEL C. BAUGHN
